DESIGN FOR A BURIAL CASKET OR SIMILAR ARTICLE

Harry A. Neff, Bellaire, Ohio, assignor to The Belmont Casket Manufacturing Company, Columbus, Ohio, a corporation of Ohio

Application June 3, 1944, Serial No. 113,853

Term of patent 14 years

(Cl. D19—1)

To all whom it may concern:

Be it known that I, Harry A. Neff, a citizen of the United States, residing at Bellaire, in the county of Belmont and State of Ohio, have invented a new, original, and ornamental Design for a Burial Casket or Similar Article, of which the following is a specification, reference being had to the accompanying drawing, forming a part thereof.

Fig. 1 is a side elevational view of a burial casket or similar article showing my new design; Fig. 2 is an end elevational view thereof; Fig. 3 is a top plan view.

I claim:

The ornamental design for a burial casket or similar article, as shown.

HARRY A. NEFF.
